UNITED STATES PATENT OFFICE.

HAROLD KELLY, OF BIDDEFORD, MAINE, ASSIGNOR OF ONE-HALF TO
EDWARD M. LANG, JR., OF PORTLAND, MAINE.

DEVICE FOR PLUMBING SPINNING-SPINDLES.

SPECIFICATION forming part of Letters Patent No. 677,994, dated July 9, 1901.

Application filed November 23, 1900. Serial No. 37,430. (No model.)

To all whom it may concern:

Be it known that I, HAROLD KELLY, a citizen of the United States, residing at Biddeford, in the county of York and State of Maine, have invented certain new and useful Improvements in Devices for Plumbing Spinning-Spindles; and I do hereby declare that the following is a full, clear, and exact description of the invention, which will enable others skilled in the art to which it appertains to make and use the same.

My invention relates to devices for plumbing spinning-spindles; and it consists of two bifurcated wedges, the space between the bifurcations being sufficient to permit the passage of the shank of the spindle-case. Said wedges are placed one upon the other and between the top of the rail and the shoulder on the outside of the spindle-case and are provided with means for rotating the wedges upon each other and around the shank.

In the drawings making a part of this specification, Figure 1 is an elevation of a spindle and rail, showing the plumbing device in use. Fig. 2 is a top plan of two of the wedges, one superimposed upon the other. Fig. 3 is a side elevation of the same in the position shown in Fig. 1. Fig. 4 is a side elevation of the wedges shown in Fig. 2, the thickest parts being brought nearer together; and Fig. 5 is a top plan of a wedge.

In the drawings, *a* represents the rail, *b* the spindle-case, *c* a shoulder on said case adapted to support the spindle-case upon the rail, the shank *h* of the spindle-case passing downward through a hole in the rail (shown by dotted lines in Fig. 1) and being secured beneath the rail by means of a nut *g*. The wedges *d d* are preferably of like construction, so that the description of one is the description of all. The outline or outer perimeter of the wedge is circular, having upon one side a greater thickness, which diminishes regularly to the other edge, as shown in Fig. 3. At the thinnest part of the circle the material is removed, leaving a bifurcation the width of which is equal to or very slightly larger than the diameter of the shank, while it extends into the wedge to such a distance that the part of the wedge left remaining at its thickest part is equal to the difference be-

tween the circumference of the shank and the circumference of the shoulder *c*. I prefer in actual construction to remove from the disk a circular portion concentric with the circle or outside circumference of the wedge, together with that part of the annulus occupying the thinnest part of the wedge, leaving the wedge of the shape shown in Fig. 2. The wedge is also provided, preferably at the thickest part, with an ear *f*, (see Fig. 2,) which may be turned upward, as shown in Figs. 1, 3, and 4; but any convenient means for rotating the wedge may be substituted for the ear *f*. 65

In operation the wedges are interposed between the rail *a* and shoulder *c*, one wedge being imposed upon the other, as shown in Fig. 1. It will be readily seen that by loosening the nut *g* the wedges can be moved one upon the other, thus restoring the spindle-case to a perpendicular position when it has become out of line. This vertical or perpendicular position of the spindle-case is very desirable, as well as a convenient means by which the spindle-case can be restored to its perpendicular position. Disks have been heretofore used for this purpose; but in order to apply them not only must the nut be loosened but removed from the shank of the spindle-case and the case from the rail in order that such disks may be placed in position, and the spindle-case and nut must then be replaced. The same process must be gone through when one or more of the disks become worn or broken, so that its replacement may be made. The device which is described in this specification is therefore much more convenient and much more easily applied, both in the case of original application and in case it becomes necessary to substitute a new part for one injured, worn, or broken, as all that is required to be done is to slightly loosen the nut, insert from opposite sides the wedges, the bifurcations passing on either side of the shank, and then, having adjusted the spindle-case to a perpendicular position by means of the wedges, set up the nut. 90

What I claim is—

1. In a plumbing device for spindles, the combination with a spindle-case having a projecting shoulder thereon and a supporting-

rail, of bifurcated wedges, said wedges being placed one upon another and interposed between said rail and said shoulder and adapted to rotate around said case, substantially as and for the purposes set forth.

2. In a plumbing device for spindles, the combination with a spindle-case having a projecting shoulder thereon and a supporting rail, of wedges having bifurcations adapted to receive the shank of the spindle-case, said wedges being placed one upon another and interposed between said rail and said shoul-

der and adapted to rotate around said case, together with means for rotating said wedges, substantially as and for the purposes set forth.

In testimony that I claim the foregoing as my invention I have hereunto set my hand this 12th day of November, A. D. 1900.

HAROLD KELLY.
